United States Patent

Des. 236,892
Patented Sept. 23, 1975

236,892

WALL HYDRANT

Donald E. Carlson, Highland Park, Ill., assignor to
Mark Controls Corporation, Evanston, Ill.

Filed Feb. 19, 1974, Ser. No. 443,309

Term of patent 14 years

Int. Cl. D23—01

U.S. Cl. D23—12

FIG. 1

FIG. 2

FIG. 4

FIG. 3

FIG. 5

FIG. 6

FIG. 1 is a front perspective view of a wall hydrant embodying my new design;

FIG. 2 is a top plan view thereof;

FIG. 3 is a front elevation view thereof;

FIG. 4 is an end elevation view thereof;

FIG. 5 is an elevation view taken from the end opposite that shown in FIG. 4; and

FIG. 6 is a bottom plan view thereof.

I claim:

The ornamental design for a wall hydrant, substantially as shown.
